(57) **CLAIM**

I claim the ornamental design for a double-wide modular display fixture, as shown and described.

DESCRIPTION

FIG. 1 is a perspective view of a double-wide modular display fixture in use;

FIG. 2 is a perspective view of the double-wide modular display fixture;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines in the drawings are included for purposes of illustrating environment and form no part of the claimed design.
